Application October 16, 1952, Serial No. 21,863

Term of patent 7 years

(Cl. D58—11)

To all whom it may concern:

Be it known that we, Benjamin Greenstein and Carl Molk, both citizens of the United States, residing at the Bronx, New York, and New York, respectively, in the counties of Bronx and New York respectively, and both in the State of New York, have invented a new, original, and ornamental Design for a Metal Box, of which the following is a specification, reference being had to the accompanying drawing, forming part thereof.

In the drawing:

Fig. 1 is a top plan view of a metal box, showing my new design, the ornamentation shown completely within one quadrant being repeated in the remaining quadrants on the top of the box; and

Fig. 2 is a front perspective view of the same.

The rear view of the metal box is the same as that shown in Fig. 2.

I claim:

The ornamental design for a metal box, as shown and described.

BENJAMIN GREENSTEIN.
CARL MOLK.
